SWINGLETREE AND TRACE CONNECTION.

955,613.

Specification of Letters Patent. Patented Apr. 19, 1910.

Application filed September 28, 1909. Serial No. 520,016.

To all whom it may concern:

Be it known that I, WILLIAM A. STINSON, a citizen of the United States, residing at Greenwood, in the county of Leflore and 5 State of Mississippi, have invented certain new and useful Improvements in Swingletree and Trace Connections, of which the following is a specification.

This invention relates to swingletree and 10 trace connections.

It is common to provide swingletrees with spring connections adapted to be compressed upon the application of the trace thereto, which springs snap back into normal position after the trace has been positioned for 15 the purpose of preventing accidental disconnection of the trace from the swingletree. It is common to form swingletrees peculiarly to prevent accidental displacement of the 20 traces.

The spring connections referred to are not altogether practical, because of breakage, complications and other defects, which render them otherwise unsatisfactory. In 25 cases where the swingletree has a peculiar formation, the application of an entirely new swingletree is necessary in the event of breakage, and even where the swingletrees are of peculiar formation, it is generally 30 necessary to provide other means of some sort for association with the swingletrees to prevent accidental displacement of the traces.

In the present instance, I provide an exceedingly simple fastening, which may be 35 readily applied to any type of swingletree and quickly removed, if desired, all without affecting the strength of the swingletree and without marring the appearance thereof.

Another object resides in the provision of 40 an exceedingly simple button connection which may be applied to any type of swingletree and which, when applied, will not be subject to breakage, disconnection, or in- 45 convenience to the person applying or removing the traces from the swingletrees and yet prevent accidental displacement of the traces.

With the above and other objects in view, 50 the present invention consists in the combination and arrangement of parts hereinafter more fully described, illustrated in the accompanying drawings, and particularly pointed out in the appended claim, it being 55 understood that changes may be made in the form, proportion, size and minor details

without departing from the spirit or sacrificing any of the advantages of the invention.

In the drawings:—Figure 1 is a top plan 60 view of a portion of one end of a swingletree illustrating the trace applied thereto in position as not to become accidentally disconnected from the swingletree. Fig. 2 is a detail view of a modified form of button. 65

Referring now more particularly to the accompanying drawings, the reference character 1 indicates a portion of a swingletree 70 into the back of which is screwed the screw threaded shank 2 of a button 3, it being understood that one of these buttons 3 is to be used at each end of the swingletree.

Swingletrees usually taper toward their ends, as may be gathered from the accompanying illustration, but in any event, the 75 ends of the swingletrees are usually comparatively small so that the opening 4 of a trace 5 may be readily slipped over the ends of the swingletree.

In the present instance, the head of the 80 button 3 disposed adjacent the extremity of the swingletree is rounded, so that the opening 4 may be readily slipped over the same. The inner side 6 of the button 3 is preferably flat and straight so as to provide a 85 shoulder against which the inner end of the trace may rest, as clearly shown in Fig. 1 and by virtue of which the trace is not subject to accidental disconnection from the 90 swingletree.

Instead of screwing the buttons 3 into the swingletrees, as hereinbefore described, they may be driven into the same, as evidenced by the form of button shown at 7 in Fig. 2, wherein the shank 8 of the button 95 7 is provided with prongs to prevent disconnection of the button from the swingletree. The main difference between the two types of buttons is that the first one is removably connected to the swingletree, while the second one is permanently associated therewith. 100

From the foregoing, it will be apparent that in the event of breakage of the trace 105 connections of the ordinary type, one of my improved buttons may be readily put into service or that, if desired, old types of connections may be removed from swingletrees and my improved button associated therewith. 110

What is claimed is:—

An attachment for whiffletrees consisting

of a button having a relatively tall body portion which has one flat edge to form a shoulder, the opposite edges of the body portion merging into said flat edge, the bottom of the body portion being flat and having a reduced centrally disposed securing shank.

In testimony whereof I affix my signature in presence of two witnesses.

WILLIAM A. STINSON.
